SKATEWHEEL CONVEYOR PALLET

Theodor M. Box, 1108 Aileen Road,
Brielle, N.J. 08730

Filed Apr. 2, 1975, Ser. No. 564,420

Term of patent 14 years

Int. Cl. D9—99

U.S. Cl. D12—53

Fig. 2.

FIG. 7.

FIG. 1 is a top plan view of a skatewheel conveyor pallet showing my new design;

FIG. 2 is a bottom plan view thereof;

FIG. 3 is a side elevation view thereof;

FIG. 4 is an end elevation view thereof;

FIG. 5 is a side elevation view thereof in section, taken along lines 5—5 of FIG. 1;

FIG. 6 is an end elevation view thereof in section, taken along lines 6—6 of FIG. 3; and

FIG. 7 is a top plan view of a skatewheel conveyor pallet showing a second embodiment of my new design, the sole difference being in the length thereof.

I claim:

The ornamental design for a skatewheel conveyor pallet, as shown and described.
